ASSIGNORS, BY MESNE ASSIGNMENTS, TO BARBER-COLMAN COMPANY, OF ROCK-
FORD, ILLINOIS, A CORPORATION OF ILLINOIS.

METALLIC HEDDLE MECHANISM FOR TEXTILE-MACHINES.

1,379,099.

Specification of Letters Patent. Patented May 24, 1921.

Application filed July 10, 1916. Serial No. 108,387.

To all whom it may concern:

Be it known that we, EDGAR F. HATHAWAY and CHARLES M. MARS, both citizens of the United States, and residents of Dorchester, in the county of Suffolk and State of Massachusetts, have invented an Improvement in Metallic Heddle Mechanism for Textile-Machines, of which the following description, in connection with the accompanying drawings, is a specification, like characters on the drawings representing like parts.

This invention relates to textile machines, being more particularly concerned with machines for selecting and separating warp threads and presenting them successively to the action of some mechanism, such for example, as a thread placing device or member, and particularly relating to means for controlling the drop wire instrumentalities thereof, and the parts, elements and mechanisms particularly co-acting with such means. For purposes of illustration, the invention is herein shown embodied in a warp drawing or thread placing machine where the thread placing device is utilized for placing the warp threads through drop wires, harness eyes and reed dents. While our invention has particularly advantageous application to a machine of this class, it is, however, susceptible of broad application to machines intended for other or similar purposes than drawing-in machines wherein the selection and separation of warp or other threads is required.

The character of the invention will be best understood by reference to the following description of an illustrative embodiment thereof, shown in the accompanying drawing, wherein—

Figure 1 is an end elevation of a warp drawing machine constituting the preferred embodiment of our invention;

Fig. 1^a is a detail in end elevation of a portion of the means for controlling the movement of the warp supports or carriages;

Fig. 1^b is a front elevation of the construction shown in Fig. 1^a;

Fig. 1^c is a sectional detail of warp clamp moving means;

Fig. 2 is a front elevation of the left hand end of said machine;

Fig. 3 is a front elevation of the right hand end thereof;

Fig. 4 is a view partially in plan and partially in horizontal section upon the line 4—4 of Fig. 1, of the left hand end of the machine;

Fig. 5 is a similar view of the right hand end of the machine;

Fig. 6 is a view partially in traverse section on the line 6—6 of Fig. 2, and partially in elevation of the end clamp for the drop wire supporting bars, herein positioned at 65 the left hand end of the machine;

Fig. 7 is a front elevation thereof and the immediate supporting means therefor;

Fig. 8 is a front elevation of the carriage for positioning the drop wires in relation to 70 the releasing keys and the adjacent members of the machine;

Fig. 9 is a plan view partially in section of the construction shown in Fig. 8;

Fig. 10 is a view mainly in vertical section 75 on the line 10—10 of Fig. 2, of the parts shown in Figs. 8 and 9;

Fig. 11 is a front elevation of the opposite or right hand end support for the drop wire bars and showing also a portion of the driving means for the drop wire feeding worms, etc.;

Fig. 12 is a plan view of the construction shown in Fig. 11;

Fig. 13 is a view in vertical section on the 85 line 13—13 of Fig. 2 and showing a portion of the driving connection for the parts;

Fig. 14 is a plan view of the pattern mechanism and the driving connections for certain of the parts including the releasing keys, the drop wire feed worms and the continuous driving means for the warp worms; and

Fig. 15 is a view in section on the line 95 15—15 of Fig. 14.

While the invention in many of its aspects is applicable to machines other than warp drawing machines and also to warp drawing machines of other types and constructions than that herein shown, we have 100 herein illustrated the invention by embodiment in a well known type of drawing-in machine, which therefore need not be described in entire detail.

The machine here shown may as to certain features thereof be of the same general construction as the type of machine shown in British Patent No. 4661 of 1904, and the U. S. Patent to Charles Lea, No. 1,153,869, dated September 14, 1915.

In the illustrated form of machine, as is well known to those skilled in the art, the heddles, warp threads and drop wires or other similar loom elements which may be 5 and preferably are employed, are supported in a general parallel arrangement lengthwise the machine upon suitable supports carried by the main frame 1 of the machine. Any suitable thread placing device is provided. We have herein represented a drawing needle 2 adapted to be suitably reciprocated and carried by the traveling carriage 3, shown most clearly in Fig. 4. The said carriage with its needle is caused to traverse 10 the extent of the reed which is or may be supported in the usual manner and is not herein indicated, and the extent of the harnesses, which likewise have been omitted to permit clearness of illustration of other parts. The drawing needle is also traversed 15 the extent of the drop wires, such drop wires being of any suitable construction, and being preferably similar to those indicated in the co-pending application of Edward La 20 Chance and Joseph Pennell, Serial No. 877,769, filed December 17, 1914. Certain features herein shown are also shown in the patent to Hathaway and Lea, 1,188,070.

The needle carriage 3 is positively traversed through the machine by means herein-after described, said means being operatively related to the main operating or drive shaft 4, whereby as hereinafter more fully set forth, the needle carriage and the warp supports or carriages are positively and preferably differentially traversed through the machine by means of operating connections from the said main drive shaft 4. I use the term differential and its derivatives to mean 30 in substance at different rates.

In the usual manner, the drawing needle 2 places successive warp threads through the desired heddle eye or selected reed dent and drop wires, these being appropriately positioned for this purpose in the needle path by suitable selecting and positioning mechanism.

The drawing-in needle 2 may be operated in any suitable manner. In order to operate the same and the other portions of the mechanism, we have herein provided the main operating or drive shaft 4, which, as shown most clearly in Fig. 3, carries a driving pulley 5 receiving power from any suitable source. The said shaft is herein shown as provided with a clutch 6 and a brake 7. As shown most clearly in Fig. 1, the shaft 4 has fastened upon its left hand end viewing Fig. 2 a sprocket gear 8 (Fig. 1) 40 about which passes a sprocket chain 9 also passing about a sprocket gear 10 upon a short shaft 11 having thereon change gear mechanism diagrammatically indicated at 12 and conveying motion to a short shaft 13. 45 The shaft 13 carries a sprocket gear 14 about

which passes a sprocket chain 15 also passing about a sprocket pinion 15' on a shaft 16, which is herein represented as provided with two distinct and separate cams 17, 18, most clearly indicated in Fig. 1^b, and which may be relatively positioned as desired and of different extent and contour, thereby to effect the independent control of the warp supports or carriages hereinafter referred to and at different rates of speed if desired, 70 with respect to each other and (or) to the needle carriage.

The needle carriage 3 hereinbefore referred to as positively traversed along the machine is herein provided for that purpose 80 with a divided nut 18' indicated in Fig. 4 and adapted to be placed through manual control or otherwise in suitable relation with a thread 18'' upon the cam shaft 16, which thus constitutes a lead screw shaft for traversing the needle carriage along the machine and a cam shaft for effecting the traverse of the warp supports or carriages along the machine.

The means for thus positively and differentially operating the needle carriage and a warp supporting means broadly, may be that disclosed in the co-pending application of Field, Lanning, Hathaway & Blanchard, Serial No. 142,251, filed February 6, 1903, wherein, however, but a single warp supporting means was provided, for the single warp there disclosed.

The needle 2 may be operated in any suitable manner. As herein shown it is actuated from the main operating or drive shaft 4 through gearing indicated at 19 in Fig. 4 meshing with a gear splined and slidable on the main drive shaft 4, whereby is rotated the shaft 20 mounted upon the needle carriage and having thereon a crank wheel 21 connected by rod 22 with a lever arm 23, the lower end whereof is fulcrumed upon the needle carriage 3 and the upper end whereof is connected by a link 24 to the holder for the needle 2, whereby the latter is reciprocated in the suitable guide provided therefor. If desired and preferably we provide a needle stripper indicated generally at 25 in Fig. 4 and suitably operated 115 from the shaft 20 through a shaft 26, bevel gearing 27 and other parts not necessary to describe in detail.

The separate banks or groups of drop wires are supported or threaded upon longitudinally extending bars 28, shown in Fig. 4 as three in number. Any suitable number of drop wire supporting bars may be provided. They may be loom bars or special bars onto which the drop wires are transferred from the loom bars. We provide suitable feeding means for said drop wires and for that purpose have indicated in Fig. 4 shafts 29 carrying drop wire feeding worms 30, preferably of the general con- 120 125 130

struction disclosed in the said application of La Chance and Pennell. To rotate the shafts 29, any suitable means may be provided. For that purpose, we have diagrammatically indicated a gearing box 30' in Fig. 4, wherein are suitably mounted gears for rotating said shafts 29. Motion is imparted to the gearing in said box by a gear 31 upon a shaft 32 indicated in Fig. 4, said 10 shaft being driven in a manner more fully hereinafter set forth.

In order to release the drop wires upon the bars 28, we preferably provide releasing keys corresponding in number to the sets of drop wires and each mounted upon a shaft, the rotation whereof is controlled by suitable pattern mechanism. The releasing keys extend through openings in the drop wires in the general manner disclosed in the 20 said patent to Lea, No. 1,153,869, whereby at suitable times drop wires are released and are delivered to the worms 30.

The pattern mechanism is diagrammatically indicated at 33 in Fig. 5, and will be 25 more fully hereinafter described. It is so constructed and arranged that the releasing key shafts may be operated in any combination or sequence or variable order that is desired, thereby to release drop wires from 30 any bar 28, to the feeding action of the feed worms 30. For example, the said shafts and the warp worm shafts hereinafter described and which are also controlled by the pattern mechanism, may be operated in a repeated 35 sequence to present warp threads and drop wires to the needle or a plurality of threads may be presented by one worm shaft followed by the presentation of a plurality of threads by another worm shaft or the said 40 worm shafts may be operated simultaneously to present threads to the needle so that two warp threads would be drawn in at the same time. The feeding of warp threads from each warp support or carriage is independent of the feeding of warp threads 45 from the other warp support or carriage, and the same is true of the releasing of the drop wires, as well as of the heddles, hereinafter referred to.

50 In the disclosed embodiment of the invention, we provide a plurality and herein specifically a pair of independent warp supporting means or carriages which are independently traversed through the machine. 55 We effect the independent automatic control of the said two warp supports or carriages, and we preferably also arrange for hand control of either of said carriages and as herein disclosed in a selective manner and, 60 as above stated, we provide for the pattern control of the individual warp threads of the said carriages. These purposes and objects of our invention may be effected in many different ways. We shall, without in 65 any way limiting ourselves thereto, proceed

to describe the selected embodiment of means for effecting the desired results. In accordance with our invention, we impart movement to the warp carriages which are differential either with respect to each other 70 or with respect to the needle carriage, or with respect to both, and we impart a compensating movement to one or both of the warp carriages, such compensating movement herein being represented as hand controlled. 75

Referring more particularly to Fig. 1, we have herein represented two warp beams 34, 35, the warp threads 36 from the beam 34 passing through a suitable two-part clamp 37 mounted for sliding movement longitudinally of the machine in suitable guides 38 provided in suitable brackets 39, one at each end of the machine and supported upon the end uprights of the framing. The warp 85 threads 36 extend from the clamp 37 to and about a warp worm 40 and thence to a second two-part clamp 41. The shaft 40' upon which the warp worm 40 is mounted is suitably and herein loosely supported at the 90 left hand end of the machine in a bracket 42 as indicated in Figs. 1 and 4, and at the opposite end of the machine the shaft 40' is suitably supported for rotative movement 95 imparted thereto in a manner hereinafter more fully set forth. The said warp worm 40 and the corresponding warp worm for the warp carriage constitute separating, selecting and feeding mechanism for the individual warp threads. Preferably each warp 100 worm comprises a frusto-conical, fluted portion, which first receives, disentangles and separates the warp threads, and a selective feeding or spacing screw or worm portion by 105 which the threads are presented to the hook of the drawing-in needle 2 successively.

The warp threads 36' from the second warp beam 35 pass through a suitable two-part clamp 43 mounted similarly to the 110 clamp 37, in suitable guides 44 provided in said brackets 39 at opposite ends of the machine. The said warp threads 36' thence pass about the warp worm 45 supported in general parallel relation to the warp worm 115 40 and driven in a suitable manner, and from thence said warp threads pass through a two-part clamp 46, said two warp worms 40, 45 being within convenient range of the drawing-in needle.

120 The two warp worms 40, 45 are each intermittently driven from the main drive shaft 4 and the intermittent driving thereof is controlled by said pattern mechanism 33, hereinafter more fully described, whereby 125 said worms 40, 45 are independently rotated. Thus in the disclosed embodiment of our invention, we selectively drive through the pattern mechanism the warp worms 40 and 45, and the key releasing shafts for the drop 130

- wires, and in addition we also so drive through the control of the pattern mechanism the heddle selecting elements, as hereinafter set forth.
- 5 We have herein provided an independent support or carriage mechanism for each of the sets of warp threads. Herein the warp clamps 37 and 41 constitute the support or carriage mechanism for one set of warp threads and the clamps 43 and 46 constitute the support or carriage mechanism for the other set of warp threads, although the clamps of each support are structurally distinct. Any suitable means may be provided whereby independently and if desired differentially the two pairs of clamps, that is, the two supports or carriage mechanisms, may be traversed through the machine in addition to which, as hereinafter set forth, we provide a compensating movement for both of said warp supports, and preferably though not necessarily this is effected through manually controlled means. Preferably, however, we employ as previously stated the two cams 17, 18 upon the lead screw cam shaft 16. Said cams may be of any desired extent and shape to effect a differentiation in speed of the feed of the two warp supports or carriages.
- In order to convey motion from the said cams 17, 18 to the said two carriage mechanisms, we have herein provided the following co-acting instrumentalities.

Upon a stud 47, shown most clearly in Figs. 1^a and 1^b are independently pivoted two levers 48, 49, either or both of which may be held out of action by latches, one of which is indicated at 49' in Fig. 1^a. These levers are provided with projections 49'', which are adapted to be held against the cams 17, 18 by springs 49''', as disclosed most particularly in the co-pending application of Edgar F. Hathaway, Serial No. 108,380. Said levers 48, 49 are pivotally connected to rods 50, 51, the other ends of which are pivotally connected to suitable levers, themselves pivotally mounted upon suitable pins 56, 57 carrying second levers which are mounted upon stud 60, 61 extending from the framing. Upon said studs 60, 61 are loosely mounted suitable worms 62, 63 carrying or having integral therewith ratchets 64, 65 with which mesh pawls 66, 67 upon the said pins, whereby in the rotation of screw shaft 16 the cams 17, 18, impart intermittent and independent rotation to the said worms 62, 63.

The means for imparting rotative movement to each of said worms 62, 63 may be and preferably is similar to or the same as the means disclosed in the said application of Field, Lanning, Hathaway & Blanchard, Serial No. 142,251, for imparting rotative movement to the worm disclosed therein, whereby the single warp carriage or support is traversed through the machine.

In order to transmit motion to the clamps 37, 43, from the said worms 62, 63, we have provided each of said clamps with a rack 68, 69 (Fig. 1) formed upon or attached to the inner face thereof and with the teeth of which said worms 62, 63 respectively mesh, whereby said clamps are independently and if desired differentially traversed along the machine, in an automatic manner.

In order that the corresponding clamps 41, 46 constituting portions of said warp carriages, may be traversed through the machine, each in unison with its corresponding clamp 37, 43, we may employ any suitable means. Herein we have mounted each of said clamps 41, 46 in the generally U-shaped brackets 70, 71. Each of said brackets has formed or mounted upon the lower face thereof a rack 72, with which meshes a worm 73 loose upon a stud shaft 76, laterally extending from a block 78 (one of which is shown in Fig. 1^c). The blocks 78 are mounted for sliding movement upon the rods 80, 81 pivotally mounted at 82 in the end brackets 39, it being understood that preferably at each end of the machine, we provide the described means supporting the said clamps 41, 46, the driving means therefor being, however, provided only at one end of the machine. The said rods 80, 81 may be adjusted to any desired angle or inclination in their pivotal supports and clamped in the desired position to secure the proper tensioning and positioning of the warp threads.

In order to convey unison movement to the clamps 37, 41 and clamps 43, 46, we may provide any suitable means but herein we have shown two endless sprocket chains 83, 84 passing about suitable sprocket gears 85, 86 fast with the said worms 62, 63 and also passing about sprocket gears 87, 88 upon stud shafts 89, 90 mounted in suitable bearings upon a stationary shaft or support 91 extending from the frame upright at the left hand end of the machine as most clearly shown in Fig. 1. Said sprocket chains 83, 84 also pass about idler sprocket pinions 92, 93 suitably mounted and supported by the framing. Said sprocket chains mesh as shown with sprocket gears 95, 96 respectively fast with the worms 73, whereby the clamps 41 and 46 are driven. The said chains also extend about idler sprocket gears 97, 98, each carried by a suitable block adjustably mounted at the outer ends of said rods 80, 81, and also about suitable idler sprocket pinions 99, 100 mounted upon the adjacent brackets 39 and thus are returned to the respective sprocket gears 85, 86 upon the worms 62, 63.

In this or in any other suitable manner, unison movements are imparted to the clamp 37 and the clamp 41, constituting or comprising a portion of one warp carriage,

and are also imparted to the clamps 43, 46, constituting or comprising a portion of the other warp carriage.

As herein shown, the upper and lower 5 clamps of the respective carriages are not mounted or held in a common housing or member, but they are operatively connected so as respectively to move together and thereby constitute portions of the respective 10 warp supports or carriages.

In addition to the independent automatic control of the plurality of warp supports or carriages, we preferably provide for a selective hand control of either of said warp supports or carriages, and preferably whereby such hand control may be exercised first upon one and then upon the other of said warp supports or carriages, or in any desired order whereby compensating movement 15 is imparted thereto.

For this purpose we have herein represented as pivotally mounted at 101 at each end of the machine upon the frame upright a lever arm 102, herein shown as having pivotally connected thereto intermediate its 20 ends a link 103 pivotally connected at its upper end at 104 to a lever arm 105 itself pivoted at 106, thereby providing parallel motion means to effect and secure the proper movement of said lever arms 102. The outer free end of each lever arm 102 is provided with a transverse slot 107 having loosely mounted therein a shaft 108 on which is splined a pinion 109 adapted to mesh with either a pinion 110 fast with the sprocket 87 or with a pinion 111 fast with the sprocket 88, the construction being such that the pinion 109 remains in mesh with whichever pinion 110 or 111 it is manually brought 25 into engagement. The pinion 109 is, as stated, splined upon the shaft 108 whereby said pinion may remain in mesh with either the pinion 110 or the pinion 111, while permitting longitudinal movement of said shaft 30 108, preferably manually, thereby to control the clutch mechanism of the machine in a manner similar to that disclosed in the patent to Hathaway and Lea, No. 1,169,087, dated January 18, 1916. In this manner, 35 the machine may be stopped or started by the operator wherever he may be standing between the ends thereof. The said shaft 108 in Fig. 3 is bifurcated at 112 for the 40 passage of the upper curved portion 113 of the upright lever 114 pivoted at 115 and operatively connected in a manner not herein necessary more fully to describe with the clutch 6 of the machine.

When it is not desired to impart hand adjustment to either warp support or carriage, the shaft 108 may be swung by the operator into an elevated or non-active position by a movement of the lever arms 102 upwardly about the points 101, said arms being then 45 supported in such non-active position by any

suitable latch or other means, not herein necessary more fully to describe.

We may, if desired, provide means manually to drive the main drive shaft 4 and the various parts controlled thereby. For this 50 purpose, and as shown most clearly in Figs. 1, 2 and 3, a longitudinally extending shaft 116 is mounted in suitable bearings 117, 117, provided in the end uprights, and having if desired one or more hand wheels 118 to effect 55 more ready rotative movement of said shaft. If desired, clutch or other means 118' may be provided to prevent rotation of the shaft 116 in the wrong direction. At the left-hand end of said shaft, we have 60 provided a bevel gear 119, meshing with a similar gear 120 upon an inclined shaft 121 extending in a downward direction into proximity to the main drive shaft 4, where 65 similar beveled gears (not shown) operatively connect said shafts. By disconnecting the main power drive, the entire machine may be driven manually through the 70 said shaft 116.

The machine herein disclosed may be, 75 and preferably is, provided with means whereby the desired heddles of the various groups of heddles may be selected and positioned for the passage therethrough of the drawing in needle. In Fig. 4, we have indicated six heddle selecting shafts 122, each provided with a worm 122' of the general construction shown in the patent to Lea, 1,153,869, and in that to Field, 755,861, the 80 said worms and their shafts being controlled 100 in operation by the pattern mechanism hereinafter more fully described.

It is evident that one of the warp beams 34, 35, may carry the bulk of the warp threads and the other may carry a smaller 105 number of threads, or that there may be any suitable distribution of the threads thereon. For example, the arrangement may be such that ten threads may be selected from one warp beam, and then one thread might be 110 selected from the other, thereby arranging the threads for producing a woven-in stripe effect. The threads on one beam may be of a different size from those on the other, or of a different character, or they may be 115 differentiated therefrom in any desired manner.

The bars 28, as previously stated, may be loom bars whereon in the weaving operation the drop wires are supported; or they may 120 be special bars to which for the drawing-in operation the drop wires are transferred. The said bars 28 are preferably supported in a clamp generally indicated at 132 in Fig. 2, and shown in detail in Figs. 6 and 7, 125 and hereinafter more fully described. The other ends of said bars 28 are preferably loosely supported in a bracket shown most clearly in Figs. 11, 12 and 13, and herein-after more fully described. We preferably 130

provide a packer carriage 123 broadly similar to that shown in the patent to Lea, No. 1,153,869, and by means of which the several series of drop wires may be held with suitable pressure against the respective releasing keys, so that when released they are immediately discharged into the drop wire feed worms. Said carriage 123, however, has certain features of broad novelty hereinafter 10 described.

It will be evident from the foregoing description that for each of the two sets of warp threads, we have provided two clamps, the clamps for each set of warp threads being 15 automatically traversed longitudinally of the machine, and the two sets of clamps for the two sets of warp threads being, if desired, traversed longitudinally of the machine at different rates of speed. Selective 20 hand traversing means is provided whereby in any desired order, the two sets of warp threads may be moved compensatingly, longitudinally of the machine. Selective mechanism is provided governing the presentation of the threads to the drawing-in needle, there being two separate warp worms about which the respective warp threads are wrapped. Inasmuch as said warp worms are pattern controlled, it is evident that the 25 threads may be fed to the place of the drawing-in needle in any desired order or sequence. By the pattern mechanism not only are the warp worms selectively controlled, but also the release key shafts and 30 the heddle worms, thus permitting any desired selection of the heddles, the drop wires and the warp threads.

While the drop wire supporting bars 28 may be special bars provided for and constituting a part of the mechanism, or may 40 be the loom or mill bars which in the weaving operation carry or support the drop wires, an important object of our invention is to provide suitable means whereby loom or mill drop wire bars may be positioned in 45 the drawing-in mechanism, and yet the threading of the drop wires,—that is, the passage of the drawing-in needle through the openings therein provided for the purpose,—may be accurately carried out. We have discovered that the under edges of the 50 loom or mill drop wire supporting bars are apt to be exceedingly irregular, and to become worn in the weaving operation because 55 the shedding action constantly lifts the drop wires against the said under edge of said bars. On the other hand, the upper surfaces of said bars receive very little wear, inasmuch as the drop wires in practice contact 60 therewith substantially only when a warp thread breaks, and such contact is momentary or for a very brief period. Inasmuch, therefore, as the upper edges of the loom or mill drop wire supporting bars are straight 65 and unworn, we have availed ourselves of

this fact, and have so located and positioned the said loom or mill drop wire bars in the machine and determined the exact positioning of the upper edges thereof, that in the drawing-in action, the drop wires are positioned with respect to the said upper edges, and, as this is an unvarying position, the warp thread receiving opening in each drop wire is always accurately positioned at the proper level for the passage of the drawing- 70 in needle. In order to secure these and other results, we have provided the following mechanism, to which, however, our invention is not limited.

Referring particularly to Figs. 4, 6 and 7, 80 we have therein indicated a fixed shafting 124 extending forwardly from the left-hand end upright of the machine. Thereon is received a bearing member 125, having a transverse hub portion 126, wherein is received 85 an elongated spindle or rod 127, which, as shown in Fig. 7, is provided with a groove 128 to receive the end of a set screw 129 tapped into the collar 130. By loosening said set screw, the spindle or rod 127 may be 90 slid through the bearing 126 so as to carry inwardly or toward the right, viewing Fig. 7, the end support or clamp for the drop wire supporting bars. An important purpose of this construction is to adapt the 95 machine to support various lengths of drop wire supporting bars. Certain of such loom or mill bars may be or are of comparatively short length. By the described or other suitable adjustment, we have provided for 100 the reception and support of many different lengths of drop wire supporting bars.

Passing through and adjustably mounted in the spindle or rod 127 is a spindle or stud 131 upon the upper end of which is received a block or bracket 132 held in the desired position of vertical adjustment by a set screw 133. Secured to or forming a part of the block or bracket 132 is a depending, or plate-like, member 134 having formed 110 with or secured thereto an inwardly projecting base portion 135. Positioned beneath the base 135 is a plate 136, through which loosely pass pins 137, each having a head 138. Surrounding each of said pins is 115 an expansive spring 139, and carried by the upper ends of each of said pins is a head or socket member 140 having a slot or groove 141 therein to receive the respective drop wire supporting rod 28. Loosely passing 120 vertically through the inwardly extending head portion 142 of the block or bracket 132 is a spindle 143, the lower threaded end 144 of which is tapped into the threaded opening 145 in the base portion 135, and takes against 125 the upper face of the plate 136 at 146. The upper end of the spindle 143 is provided with a handle 147 by which it may be suitably turned.

By sufficiently advancing the threaded 130

portion of the spindle 143 in the threaded opening 145, the plate 136 is depressed, thereby moving downward the socket members 140 against the action of the springs 5 139 sufficiently from the head 142 to permit the ready insertion or removal of the drop wire supporting bars 28. By turning the spindle in the opposite direction, the sockets 140 are permitted to be moved upwardly by 10 the expansion of the springs 139. Each socket 140 may contain a transverse pin over which the transversely notched end of the appropriate bar 28 may be hooked. In this manner, the drop wire bars 28 may 15 be tightly clamped in proper position, it being understood that the under face 148 of the head portion 142 of the clamp is fixed at the height or level that determines the proper 20 positioning of the warp thread receiving eye, or drawing-in needle receiving eye, of the drop wire. At their opposite ends, the drop wire supporting bars 28 are loosely positioned in slots 149 in a bracket 150 shown in Figs. 11, 12 and 13, as extending 25 upwardly from a gear box 30' hereinafter described.

The springs 139 also perform another function. They normally are to hold the upper edges of the drop wire supporting 30 bars 28 against the under face 148 of the head 142. They, however, permit the slight downward movement of said supporting bars 28 and the drop wires, if in the drawing-in action the needle meets the drop wires 35 slightly below the center of the needle or thread receiving opening of said drop wires.

Intermediate the opposite end supports for the drop wire supporting bars 28 is positioned the carriage 123 heretofore referred 40 to as mounted upon and longitudinally movable along the tracks 124'. As most clearly shown in Figs. 8 and 10, the said carriage is provided with rolls 125', 126', adapted to travel along the upper and lower faces of 45 said tracks 124'. The said carriage is provided with an upwardly extending relatively thin body portion 127', herein passing between two of the bars 128' that support the lower ends of the drop wires substantially up 50 to the time when they are released by the releasing keys, said bars 128' being vertically adjustable at both ends in any suitable manner. The upper end of said body portion 127' is provided with a head 129' longitudinally grooved for the reception of three so-called equalizers 130', 131', 132', each 55 of said equalizers, as shown in Fig. 10, being itself longitudinally grooved at 133' for the reception of the rods 133'' for the release keys.

In the operation of the mechanism, said equalizers 130', 131', 132', are pressed against the inner ends of the banks of drop wires, so as to hold them against the releasing keys 60 in position to be released therefrom. Inas-

much as in practice the drop wires are or may be released by the releasing keys according to the call of the pattern, it follows that, during the operation of the machine, unequal numbers of drop wires are contained in the several banks of drop wires. For this reason, and in order that uniform pressure may be obtained on all the banks of drop wires, we have provided the equalizers 70 130', 131', 132', which by pressure upon such banks of wires maintain an equality of pressure of said wires against the releasing keys. Furthermore, because of the use of equalizers, it is unnecessary to start the operation with an equal number of drop wires in 75 the several banks.

In order to preserve the equality of pressure action of the equalizers 131', 132', the inner or adjacent faces thereof are toothed as represented at 135', 136', and therewith 80 mesh the teeth upon a pinion 137', so that if one of said equalizers advances under the call of the pattern, the other one is correspondingly retarded. The equalizer 130' is 85 yieldingly pressed forward by a contractile spring 138' connected at one end to a pin 139' laterally extending from said equalizer, and at the other end to a screw 140' upon the head 129' of the carriage 123.

It has been stated that the position of the 90 upper edge of the drop wire bars 28 determines the position of the thread receiving openings of the drop wires, and that the position of the said upper edge is fixed by the under face 148 of the top piece 142 of the 95 clamp. In order that the upper edge of each of said drop wire supporting bars 28 may be maintained level throughout the extent of said bars, or at least past the drawing-in point, we have provided the following construction, to which, however, our invention 100 is not limited.

Upwardly extending from the head 129' of the carriage is a spindle 141', the upper end of which is threaded as indicated at 142', 110 to receive nuts 143' determining the vertical position on the spindle of a sleeve 144', provided with a laterally extending portion 145' having a transverse opening 146', wherein is received a sleeve 147' on which sleeve is pivoted a lever 148' having an operating handle 149'. The said lever is provided with a cam head 150', adapted to act against the laterally extending portion 151' of a sleeve 152', 115 loosely mounted upon the spindle 141' and normally upwardly pressed by the action of an expansive spring 153' surrounding said spindle. Removably received within the sleeve 147' is a pin 154', which if desired may be attached to the upper end of the 120 spindle 141' to prevent loss or displacement. Said pin 154' is provided with a series of circumferential grooves 155' corresponding in 125 number with the number of drop wire supporting bars 28, herein shown as three.

The position of the nuts 143' is such that the under side of the grooves 155' is at the same height or level as the under face 148 of the top piece 142 of the clamp.

Each of said drop wire supporting bars 28, as most clearly shown in Fig. 10, rests in a groove 156' in a block or plate 157' mounted upon a spindle 158' upwardly extending from the base of the portion 151' of the sleeve 152', which portion 152', as shown most clearly in Fig. 10, is of general U-shape. When, therefore, the lever 148' is in the position shown in Fig. 8, the drop wire supporting bars 28 are forced firmly upward into the grooves 155' of the pin 154', thereby maintaining the upper edges of said bars 28 level. When it is desired to move the carriage 123' toward the left, viewing Fig. 8, the lever 148' is turned contra-clockwise viewing said figure, thereby depressing the sleeve 152' against the action of the spring 153'.

The needle carriage and gear head are rigidly connected together as hereinafter described and travel longitudinally through the machine toward the right, viewing Fig. 8. The carriage 123 is therefore in the drawing-in operation gradually moved toward the right, viewing Fig. 8, but at the same time, it is subjected to means tending to draw it toward the left, viewing Fig. 8, in a manner not herein necessary fully to disclose, as it may be similar to that shown in the patent to Charles Lea, 1,153,869, Sept. 14, 1915. Herein, for the purpose, we preferably provide a drum having a coiled spring, from which drum extends a metallic tape or ribbon 158a, (Fig. 8) the end of which is adapted to be received by the hook 159' upon the under side of the carriage 123. It will be understood that the drop wires are released by the releasing keys at the left-hand side of said carriage 123, viewing Fig. 8. It will further be understood that the longitudinal extent of the supporting bars 128' is such that, just before each drop wire reaches the threading position, it drops off the end of its supporting bar 128', and is then supported upon the upper edge of its bar 28. It will further be understood that the drop wire supporting bars 28 are held yieldingly against the under side of the pin 154', and that the action of the spring within the drum is such as to overcome the friction between the bars 28 and the pin 154', and to exert a pull upon the carriage 123 toward the left, viewing Fig. 8.

In the disclosed embodiment of our invention, we have, in Figs. 4, 14 and 15, represented six heddle manipulating rods 122, each provided with a worm 122' (Fig. 4). The number of these rods, of course, may be varied in different machines. Each of said rods is rotated at the call of the pattern mechanism. In Fig. 15, we have rep-

resented the reed opener shaft 160, this being also rotated in accordance with the call of the pattern in a manner not herein necessary more fully to describe. The release key rods 133' are also rotated at the call of the pattern as well as the two warp worms 40 and 45. In the disclosed embodiment of our invention, however, the shafts or rods 29 carrying the drop wire feed worms 30 are continuously rotated. We have already stated that the shafts 29 for the said drop wire feed worms 30 extend into a gear box 30'. As shown most clearly in Figs. 11, 12 and 13, the gear box 30' has positioned therein upon each of the drop wire feed worm rods the pinions 161, 162, 163, the pinions 161, 162, being connected in rotation by the smaller pinion 164 and the pinions 162, 163 being in meshing relation with each other. The shaft 29 whereon is mounted the pinion 162 extends through the gear box 30', and has fast upon its outer end a pinion 165 (Fig. 12) meshing with the gear 31 previously referred to. The gear 31 is fast as previously stated upon the shaft 32, and, as most clearly shown in Fig. 14, has at its right-hand end a bevel pinion 166 meshing with a similar pinion 167 upon a shaft 168 extending transversely of the machine, and mounted in suitable bearings 169 upon the gear head 170. Upon the other end of the transverse shaft 168, (see Fig. 14) is a bevel pinion 171, meshing with a similar pinion 172 upon a short shaft 173 mounted in the gear head. The shaft 173, as most clearly shown in Fig. 15, has thereon a gear 175 meshing with a pinion 176 upon a shaft 177, having thereon a gear 178 meshing with a larger gear 179 upon a shaft 180. The said gear 180 meshes with a pinion 181, splined upon the main drive shaft of the machine. It will, therefore, be evident from the foregoing description that the feed worms for the drop wires are constantly rotated from the main drive shaft of the machine.

The gear 179 on the shaft 180 meshes with a gear 182 fast upon a shaft 183, as most clearly shown in Fig. 15, and said gear 182 meshes with and drives a pinion 184 upon a shaft 185. By reason of the Geneva-like stop motion 186, 187, the gear 188 upon the shaft 189 is intermittently rotated. Said gear 188 meshes with and intermittently rotates a pinion 190 upon the reed opener shaft 160, but as indicated in Fig. 14, the rotation of said reed opener shaft 160 is controlled by the call of the pattern.

The gear 188 also meshes with and drives a gear 191 upon a shaft 192 that meshes with a pinion 193 upon one of the harness rods 122, whereby the entire train of six harness rods is suitably driven. In order to prevent back lash, we have herein represented the gear 191 as meshing with a larger 180

gear 194 upon a shaft 195, said gear 194 meshing with one of the pinions 193 of the harness rods 122. The rotation of said harness rods is, however, subject to the call of 5 the pattern as heretofore stated.

The release key rods 133", herein shown as three in number, are in Fig. 15 represented as having thereon pinions 196 driven from the pinions 193 of the harness rods, 10 said release key rods being also controlled by the call of the pattern.

As shown most clearly in Fig. 14, the transverse shaft 168 has thereon a spiral gear 197, meshing with a similar and smaller 15 gear 198 upon a short shaft 199 extending longitudinally of the machine. Said shaft 199 is, therefore, continuously rotated from the main drive shaft of the machine through the said transverse shaft 168, and the 20 scribed connection therefrom to the said main drive shaft. Upon said constantly rotated shaft 199, as shown most clearly in Fig. 15, is a pinion 200 meshing with a gear 201, which meshes with and drives the 25 pinions 202, 203, of the warp worm shafts 40' and 45'. The rotation of said warp worm shafts is, however, controlled by the call of the pattern.

As most clearly shown in Fig. 15, the gear 30 head is provided with a base 204, having depending flanges 205 with inwardly extending bars 206, taking under the flanges 207 upon the framing of the machine. The bars 206 are rigidly connected with said gear 35 head and also with the needle carriage whereby the gear head and needle carriage move in unison, and as one member through the machine.

The needle carriage 3 carries the warp 40 worm 40 and 45 with it in its travel. The gear box 30' is connected in the usual way to the needle carriage 3 and the gear head 170 to travel therewith.

As most clearly indicated in Fig. 12, the 45 inner ends of the release key rods are movably received in chucks 208 upon shafts 209 extending through the gear box 30', and having upon their opposite ends universal joints 210, by which are driven the shafts 50 211. As most clearly shown in Fig. 14, the opposite end of said shafts 211 have universal joints 212, whereby are rotated the shafts 213, the rotation of said shafts 213 being controlled by the call of the pattern.

55 Thus, from the foregoing description, it will be evident that the rotation of the reed opener, the harness control rods, the release key rods and the warp worm rods or shafts, is controlled by the call of the pattern.

60 The pattern mechanism may be of any suitable character. It is shown in greatest detail in Fig. 14, it having been generally indicated at 33 in Fig. 5.

65 The pattern mechanism need not be described in detail, inasmuch as in its pre-

ferred form, it is like or substantially like that shown in the said co-pending application of La Chance and Pennell, like that disclosed in the application of Charles Lea, Serial No. 692,468, and like that shown in 70 the patent to Hathaway & Lea, No. 1,169,087, January 18, 1916.

It is sufficient to state that the pinions shown in Fig. 14 are adapted to be clutched to their shafts to rotate the latter at the 75 times desired. Said clutches are controlled by spring pressed rods and a pattern mechanism. Said pattern mechanism is herein represented as comprising a cylinder having perforations adapted to be brought into registration with a row of feeler bars, each having an intervening blank or separating washer. With each retraction of the drawing-in needle, the clutches of the pattern mechanism are thrown into engagement to 80 connect the driving devices of the worm shafts therewith, but are immediately released unless held by the interposition of a washer in the path of a plunger rod.

As heretofore set forth, each of the worms 90 for feeding the released drop wires is continuously rotated. Several advantages accrue from such constant rotation. Not only is there a constant drive thus secured, but a slower and easier motion is provided for. 95 Moreover a convenient arrangement of the co-operating mechanism for multiple bank work is secured, and furthermore it is possible readily to release the drop wires in any order according to the call of the pattern. 100 Heretofore it has been customary and necessary to release the drop wires in the sequence of the gearing and in a certain order. A pattern control of the drop wire release has been provided, but the arrangement has been 105 such that a regular sequence of drop wire release has been provided for, and while pauses or stops have occurred in the sequence with subsequent resumption, the release has always been in the same sequence. In accordance with our present invention, it is 110 possible through the pattern control to release the drop wires in any variable order.

In all prior mechanisms of which we are aware, there has been provided a unitary 115 drive to all drop wire mechanisms from the drive or pattern head, whereby all the drop wire mechanism in its geared sequence could be caused to dwell or be operated as desired in such sequence. In accordance with our 120 present invention, the turning worms or feeding devices for the released drop wires are constantly driven from the main head with no pattern control thereof, but with individual pattern control of the respective 125 release keys related to each turning worm or feeding device for the release keys, so that the pattern control of each of the drop wire mechanisms is had.

The support for the bars carrying or sup- 130

porting the drop wires is such that there is provided an automatic traversing justifying mechanism for the drop wires, whereby the drop wire supporting bars near the point of 5 needle operation are thrown or pressed upwardly so as constantly to position the upper edge of the supporting bars at the proper distance from the thread holes in the drop wires desired to be alined with the drawing-
10 in needle.

It will furthermore be apparent that we have provided spring tension supporting means for the ends of the drop wire supporting bars independently related to each 15 drop wire supporting bar with a common hand screw mechanism to throw the supporting means out of engagement and permit ready removal of the supporting bar.

Furthermore we have provided a sliding support for the end supports of the drop wire supporting bars 28 permitting limited longitudinal, automatic movement of the drop wire supporting bars and supporting devices. This construction is of importance, 20 inasmuch as it permits loom bars (drop wire supporting bars) to be used in the drawing-in machine where otherwise they are too short for the purpose, without transferring the drop wires from the loom bars 25 to special bars of the drawing-in machine.

We have herein referred to drop wires. This term is used generically and includes drop heddles.

It will be seen that the surface 148 (Fig. 35 7) and the bottom of the groove 155' (Fig. 10) at the lower side of the pin 154' constitute positioning means for the upper edge of each bar 28. Each bar 28 is supported at one end by means (132) on the 40 main frame, at another point by the support 150 (Fig. 11) on the main carriage, and at an intermediate point by the part 157' (Fig. 10) on the packer carriage 123. Prior to selection, the drop wires are sup- 45 ported upon the bars 128' of the main carriage.

Having thus described one illustrative embodiment of our invention, we desire it to be understood that although specific terms 50 are employed, they are used in a generic and descriptive sense and not for purposes of limitation, the scope of the invention being set forth in the following claims.

Claims:

55 1. Textile mechanism comprising in combination, thread selecting mechanism, means to support drop wires, pattern controlled releasing means for the drop wires, feeding means for the drop wires, and means to impart continuous movement to said feeding means.

2. Textile mechanism comprising in combination, means to support drop wires, pattern controlled releasing means for the drop 60 wires, feeding means for the drop wires,

and means to impart continuous movement to said feeding means.

3. Textile mechanism comprising in combination, thread selecting mechanism, means to support drop wires, pattern controlled releasing means for the drop wires, a rotary feeding device for released drop wires, and means for imparting continuous rotation to 70 said rotary device.

4. Textile mechanism comprising in combination, thread selecting mechanism, means to support a plurality of banks of drop wires, pattern controlled releasing means therefor, a feed worm for the released drop wires from each bank, and means to impart 75 continuous rotation to said feed worm.

5. Textile mechanism comprising in combination, drawing-in mechanism, a plurality of warp worms, means for supporting a corresponding plurality of groups of warp threads, means to support a plurality of banks of drop wires, releasing means therefor, pattern mechanism controlling said warp worms and releasing means, feeding means for releasing drop wires, and means to 80 impart movement of continuous rotation 90 to said feeding means.

6. Textile mechanism comprising in combination, drawing-in mechanism, a plurality of warp worms, means to support a corresponding plurality of groups of warp threads, heddle selecting means, supporting means for a plurality of banks of drop wires, releasing means therefor, pattern means for controlling the action of said heddle selecting means, warp worms, and drop wire releasing means, feeding means for released drop wires, and means to impart a movement of continuous rotation to said feeding means. 95 100

7. Textile mechanism comprising in combination, means to support drop wires, a carriage movable longitudinally of said drop wire supports, said carriage having means to position the upper faces of said drop wire supporting means in predetermined position, and means to release said drop wire supports from said carriage. 105 110

8. Textile mechanism comprising in combination, means to support drop wires, a carriage movable longitudinally of said drop wire supports, means upon the carriage to move the upper faces of said drop wire supporting means to a predetermined position, and means to release said drop wire supports from said carriage. 115 120

9. Textile mechanism comprising in combination, drop wire supporting bars, supporting means therefor, a carriage movable along said bars to coöperate with the drop 125 wires, said carriage having means to position the upper edges of said bar or bars at predetermined height, and means to release said bar or bars from said carriage.

10. Textile mechanism comprising in com- 130

- bination, drop wire supporting bars, supporting means therefor, a carriage movable along said bars to coöperate with the drop wires, means upon said carriage to position the upper edge of said bar or bars at a fixed height at the same level as the support end of said bars, and means to release said bar or bars from said carriage.
11. Textile mechanism comprising in combination, one or more drop wire supporting bars, means to support the same, said means including means to support an end of said bar or bars with the upper edge or edges at a fixed height, a carriage movable along said bars, said carriage having means to support the upper edges of said bar or bars at said fixed height, and means to release said bar or bars from said carriage.
12. Textile mechanism comprising in combination, a drawing-in device, a pair of warp worms, two carriages for independently supporting a pair of groups of warp threads, a plurality of bars for supporting drop wires, means to position the upper edges of said bars at a predetermined height, releasing means for said drop wires, and pattern mechanism controlling the action of said warp worms and releasing means.
13. Textile mechanism comprising in combination, a drawing-in device, a pair of warp worms, two carriages for independently supporting a pair of groups of warp threads, a plurality of bars for supporting drop wires, means to position the upper edges of said bars at a predetermined height, releasing means for said drop wires, heddle selectors, and pattern means controlling the action of said warp worms, said releasing means and said heddle selectors.
14. Textile mechanism comprising in combination, a drawing-in device, a pair of warp worms, two carriages for independently supporting a pair of groups of warp threads, a plurality of bars for supporting drop wires, means to position the upper edges of said bars at a predetermined height, releasing means for said drop wires, heddle selectors, a reed opener, and pattern mechanism for controlling the action of said warp worms, releasing means, heddle selectors and reed opener.
15. Textile mechanism comprising, in combination, a plurality of bars for supporting drop wires, and clamping means for fixing the position of said bars, said clamping means including a socket member 140 having slots 141, yielding supporting means for said socket member and member 134 having portion 142.
16. Textile mechanism comprising, in combination, a plurality of bars for supporting drop wires, and clamping means for fixing the position of said bars, said clamping means including a socket member 140, spring
- supporting means therefor, adjusting means 65 for said socket member, and member 134, having part 142 held in predetermined position.
17. Textile mechanism comprising, in combination, a plurality of bars for supporting drop wires, and clamping means for fixing the position of said bars, said clamping means including a member 134 having portions 142 against the surface of which the upper edges of drop wire bars are adapted 70 to be positioned, and means for forcing the upper edges of said drop-wire bars thereagainst.
18. Textile mechanism comprising, in combination, a plurality of bars for supporting drop wires, and clamping means for fixing the position of said bars, said clamping means including a member 134 having an abutment portion adapted to be fixed in predetermined position and means to force the 85 upper edge of drop wire bars thereagainst.
19. A warp-drawing machine having, in combination, a main frame, a support on the main frame for one end of a bar, a carriage for supporting a series of drop wires which 90 are strung upon said bar, a support on said carriage for the bar, a packer carriage on the first-mentioned carriage intermediate the supports for said bar, positioning means on the packer carriage to engage the upper 95 edge of the bar, and means on the packer carriage yieldingly to hold the bar up against said positioning means.
20. A warp-drawing machine having, in combination, a main frame, means on the 100 main frame for supporting one end of a bar, a carriage for supporting a series of drop wires which are strung upon said bar, a packer carriage on the first-mentioned carriage, positioning means on the packer carriage 105 to engage the upper edge of the bar, and means on the packer carriage yieldingly to hold the bar up against said positioning means.
21. A warp-drawing machine having, in 110 combination, a main frame, means carried by the main frame for positioning the upper edge of one end of a bar, means for yieldingly holding the upper edge of the bar against said positioning means, a carriage 115 for supporting a series of drop wires which are strung upon said bar, a packer carriage on the first-mentioned carriage, positioning means on the packer carriage to engage the upper edge of the bar, and means on the packer carriage yieldingly to hold the bar up against the last mentioned positioning means.

In testimony whereof we have signed our names to this specification.

EDGAR F. HATHAWAY.
CHARLES M. MARS.
